UNITED STATES PATENT OFFICE.

ELLIS F. EDGAR, OF NEW YORK, N. Y.

PROCESS OF BURNING CARBONACEOUS MATERIAL.

SPECIFICATION forming part of Letters Patent No. 402,422, dated April 30, 1889.

Application filed February 21, 1889. Serial No. 300,693. (No model.)

To all whom it may concern:

Be it known that I, ELLIS F. EDGAR, of New York, in the county of New York and State of New York, have invented certain new and useful Improvements in Processes of Burning Carbonaceous Material; and I do hereby declare that the following is a full, clear, and exact description of the invention, which will enable others skilled in the art to which it applies to make and use the same, reference being had to the accompanying drawings, and to the letters of reference marked thereon, which form part of this specification.

My invention consists in an improved process of producing heat.

Referring to the accompanying drawings, Figure 1 is a side elevation of a locomotive boiler and furnace to which my invention has been applied, part of the wall being broken away to more clearly exhibit its peculiar features. Fig. 2 is a vertical cross-sectional view on line $\alpha\alpha$, Fig. 1. Fig. 3 is a view in perspective of the attachment (partly in section) by the use of which my new process may be practiced. Fig. 4 is a view, also in perspective and with parts broken away, of a cooking-stove fitted with said apparatus. Fig. 5 is a front elevation of the fire-box of said stove. Fig. 6 is a central vertical cross-sectional view of said fire-box. Fig. 7 is a front elevation of a base-burning self-feeding parlor-stove, the novel arrangement of an apparatus for carrying out my process being shown in section. Fig. 8 is a plan view of the supporting-disk of said stove, and Fig. 9 is a similar view of the air-distributer located within said stove.

In the majority of apparatus at present used for producing heat by the combustion of coal and similar fuel much of the gas and unconsumed matter rising from the surface of the body of coal under consumption passes off into the pipe or chimney without being burned, which is a source of great waste. The present theory is that this is caused by the lack of additional air (or oxygen) supplied at the proper point and in the proper manner and quantity to combine with said unconsumed matter and result in the complete utilization of the fuel, and this is to some extent true; but it is also true that not only must additional air be furnished, but it must be

furnished in proper distribution, and there must also be provision made for igniting the combination to produce the best result; and it is in the direction of these two features that the principal novelties lie, the remainder consisting of conveniences for carrying out these principal purposes.

In the drawings, F is the fire box or space 60 of the apparatus. In Fig. 1 it is provided with ordinary grate-bars, G, and door D indeed is identical with well-known apparatus. Within this space and between the grate for the coal, C, and the draft-exit E (here located 65 above the coal) is placed a support, S, made of incombustible material, which may be a perforated diaphragm, as shown, supported by side pieces, the only requirements being that it shall permit the passage of gases from 70 one side to the other (here the lower side to the upper) through its perforations and shall be capable of supporting refractory material B, about to be described. Upon this support I place a quantity of incombustible material 75 formed or broken into small pieces of such shape that when heaped or arranged together there will be interstices between them for the passage of gas. I select material that may be raised above or to a red heat without injury, 80 fire-clay balls B, decreasing in size from the bottom to the top of the mass being preferable. Through this mass of clay balls air-conduits A' extend usually from one side to the other, being connected at the ends by a general conduit, A, opening into A' and preferably, also, into a connection leading to the outer air. These conduits A' are perforated, preferably, 85 at the sides with small apertures a, opening within the mass of clay balls in what I term 90 the "combining-chamber" of the apparatus. Such arrangement insures even and general distribution of air through the mass of refractory material B, which may be controlled by a damper, as shown in Fig. 7, if desired. It 95 is found best that air should be introduced by these means directly into the mass of refractory material B, and there combined with the gases and matter passing through said mass from s. As in this way a very small quantity of air is met by a small quantity of gas in the interstices between refractory material B the combination is instantaneous, perfect, and easily regulated as to proportions, with 100

no danger of explosion when ignited, when, if air were forced into a considerable open space, there combined with said gases, and then passed through a mass of heated balls, the combination would be imperfect, the regulation difficult, and the operation attended with some degree of danger.

In locomotive and marine boilers I usually cover the mass of refractory material B with a second diaphragm, S', also perforated, for the purpose of preventing refractory material B from being drawn out of the stack by the great draft. The fuel may be introduced through door D in the usual manner.

15 The arrangement in Figs. 4, 5, and 6 is substantially similar, the variation being in making the grate or fire-basket in the form of a drawer, D, that it may be opened to add fuel to the fire, and the conduit A is extended 20 along the front and rear; but it might readily be supplied through a door, as in the case of the furnace.

In Fig. 7, to adapt the apparatus to a self-feeding stove, a disk or damper, D', is supported upon a short post or rod, R. Above this is a cone, C', provided with openings at the base, registering with those of D' and others in its side walls. Its base projects sufficiently to sustain a circular grate, G, which, 30 as well as D', I provide with handles H. From the wall of the stove I suspend a circular lining, which, being double, forms an air-conduit, A², and other conduits, A³ and A⁴, cross-wise and circular, all connecting, are combined therewith. A² is provided with a damper, d, preferably upon its outer wall that it may not permit draft from the coal fire through A², and its base-wall projects inward, forming a rim which supports the hollow truncated cone-shaped perforated support S², which surrounds the reservoir for the coal and supports the balls B, already described, substantially as S does in the other forms of apparatus.

The whole apparatus might be supported 45 from the bottom or top or by a tripod suspended from legs on the frame; but I prefer the arrangement shown, and, too, I prefer to have the grate somewhat lower than the base of conduit A², as thereby the formation of 50 clinker is largely avoided, and what is formed, if any, may be easily removed.

Coal can be introduced into its appropriate space and fired. The heat therefrom passing through s and the interstices between refractory material B, in its natural course, quickly raises them to a high degree of heat. Then air being admitted through its conduits combines with the gases and particles of unconsumed matter passing between refractory material B, is instantly ignited by the heat of refractory material B, and produces more heat, every particle being thereby consumed and none permitted to escape and be wasted.

When fresh fuel is added in ordinary apparatus, much smoke arises and there is a temporary lowering of the temperature; but in my apparatus the smoke being combined

with air in the combining-chamber and ignited by the still highly-heated balls is consumed and no smoke results—but a great saving of 70 fuel. Then, too, the large mass of refractory material B once heated prevents the rapid variation of the temperature—a result much to be desired.

I find it desirable to have the balls B of 75 larger size at the bottom (or next the coal-space) than at the top, (or farthest from it,) as I thereby permit free combination at the bottom, and, as it were, check the escape at the top or toward it sufficiently to insure the 80 ignition of the entire combined fuel and air.

I have found by actual experiment that a high heat may be maintained for a much longer period with a given quantity of coal with this apparatus used in this method than 85 by any other known to me, and for many purposes—such as boiling—the heat from the incandescent balls is much superior to that obtained directly from a mass of burning coal.

What I claim as my invention, and desire to secure by Letters Patent, is—

1. The process of producing heat by igniting a mass of fuel, passing the flame, gas, and unconsumed particles thereof between the 95 interstices of a mass of small pieces of highly-heated incombustible material, introducing air by separate passage-ways evenly and generally throughout the interstices of said mass, there combining it with the unconsumed material of fuel passing through said interstices, and there igniting the combined mixture by the heat of said incombustible mass, substantially as set forth.

2. The process of producing heat by igniting a mass of fuel, passing the flame, gas, and unconsumed particles thereof between the interstices of a mass of small pieces of incombustible material, which said interstices are smaller at the point farthest from the 100 fuel than at that nearest to it, and which material is thereby highly heated, introducing air by separate passage-ways evenly and generally throughout the interstices of said mass, there combining it with the unconsumed particles of fuel and gas passing through said interstices, and igniting the combination by the heat of said incombustible mass, substantially as set forth.

3. The process herein described of burning carbonaceous material by first locating a mass of incombustible material in the line of draft to the chimney, then causing the gases from the combustion-chamber to enter said mass, retarding their progress and causing 115 them to take a circuitous route, then supplying air to said retarded gases in finely and evenly distributed quantities, whereby the mixture of the air and gases is brought in contact with highly-heated mass of the incombustible material, as set forth.

4. The process herein described of burning carbonaceous material, consisting in passing the products of combustion through a

highly-heated mass of refractory incombustible material, and introducing atmospheric air finely divided into said mass in such manner that it is evenly and generally distributed throughout the mass and in this state meets and mingles with the products of combustion, whereby perfect combustion takes place, as set forth.

In testimony that I claim the foregoing as my own I affix my signature in presence of 10 two witnesses.

ELLIS F. EDGAR.
